UNITED STATES PATENT OFFICE.

FRED J. KLEIN, OF NEW YORK, N. Y.

PAPER PERFORATING AND FILING DEVICE.

1,157,228.

Specification of Letters Patent. Patented Oct. 19, 1915.

Application filed May 14, 1913. Serial No. 767,513.

To all whom it may concern:

Be it known that I, FRED J. KLEIN, a citizen of the United States, and resident of New York, in the county of New York and State of New York, have invented certain new and useful Improvements in Paper Perforating and Filing Devices, of which the following is a specification.

This invention relates to devices for perforating and filing documents, letters, and other papers.

Its main object is to produce a device for use with tongued or pin paper fasteners, whereby the papers can be perforated and placed on the fasteners. It is especially adapted for use with the type of tongued paper fastener embodying a base portion and tongues or pins at or near the ends of the base, at right angles thereto.

My invention embodies means for supporting a paper fastener of this type, with the tongues in a convenient position to receive the papers, means for perforating the papers, and means for placing them on the fastener tongues. In connection with the perforating operation I have also devised special means for supporting the fastener tongues, and also means for alining the fasteners on the device.

The means I employ for accomplishing the above-mentioned objects, and various advantages of my improved perforating and filing device are illustrated in the accompanying drawings, in which,—

Figure 1 is a side elevation of the preferred form of my invention. Fig. 2 is a plan of the same. Fig. 3 is a front elevation of a portion of the form shown in Figs. 1 and 2. Fig. 4 is a plan of a portion of the same device with certain parts removed, other parts in different positions from those of Fig. 2. Figs. 5 and 6 are side elevations showing operating positions of this form of my invention. Fig. 7 is a side elevation of another modification of my invention. Fig. 8 is a front elevation of the same.

Like characters refer to like parts in all figures of the drawings.

In the form of my invention illustrated in Figs. 1 to 6, inclusive, 2 is the base, 3 is the operating lever having a handle 4 and fulcrumed on the screw 5, which is fastened into the slotted post 6 secured to the base 2 by a screw 7 and washer 8. Gage brackets 9 are also fastened to the base by screws 10, about midway of the base, one on each side.

The said brackets are slotted at 11 to support the fastener-alining member 12. The alining member 12 consists of a cross-bar 12', a right hand branch 12'', and a left hand branch 12''', both at right angles to the cross-bar, and also a rearward extending branch 12'''' carried in a slot 13 in the post. Said branch 12'''' is provided with a slot 14, through which passes the screw 15 by means of which the alining member is maintained in proper alinement. The slots 11 and 13 act as guides for said alining member 12, when it is given to and fro movements, by means of the lever 3 through the connecting link 16. Said connecting link 16 is secured to the lever 3 by a pin 17, and to the alining member by a pin 18, and when the lever 3 is at the limit of its upward and backward movement, the forward ends of the alining member are even with the front faces of the brackets 9, as illustrated in Fig. 5. The forward ends of the alining member 12, are beveled at 19, and auxiliary members 20 are riveted to the branches 12' and 12'', and have beveled faces 21. Recesses 22 are also provided, which are a trifle wider than the thickness of a fastener tongue. Clips 23 are fastened to the base 2, by means of screws, and serve to hold the paper fasteners 24, when placed in proper position. On the operating lever 3 is fastened a bar 25, having perforating slots 26, which are in alinement with the tongues 27 of the paper fasteners 24.

The operation of the preferred form of my invention described above, is as follows: The paper fasteners usually employed with my device, consist of a base 24', and tongues 27 at or near each end of the base, bent up at right angles thereto. A paper fastener of this type is placed on the base 2, with the fastener base 24' under the clips 23, and the tongues projecting upward on the outer sides of said clips. A paper or document desired to be perforated and placed on the fastener, is placed against the points 27' of the tongues, as at P, Fig. 5, and the lever 3 is then brought down, forcing the bar 25 and the paper P onto the fastener tongues, as indicated in Fig. 6, until both are arrested by the alining member 12. The lever is then moved up and back to the position shown in Fig. 5, and the paper is then pushed down by hand as far as it will go on the fastener tongues. If the fastener tongues are not spaced exactly the correct

distance apart to aline with the slots 26, or either or both do not properly aline with said slots by reason of being bent or not being properly placed, they are caused to be properly alined by the beveled faces 19 and 21 of the members 12", 12'", and 20 respectively as illustrated in Fig. 4, where continued movement of said beveled faces in the direction indicated by the arrows will cause the tongues to be bent or moved sufficiently in a lateral direction, to enter the recesses 22, where they will be in line with the perforating slots 26 of the bar 25 when they pass down to the perforating point. The papers are thus placed on the fastener tongues, one or more at a time until a sufficient number has been filed, and the fastener and papers are then removed by drawing them forward.

20 In the modified form of my device illustrated in Figs. 7 and 8, I have provided standards 32 fixed in the base 2 at right angles thereto, and mounted for up and down movement on said standards is a cross-bar 33, having two perforating slots 34. At the upper part of the standards is journaled a spindle 35, having a cam 36 secured to it near its central portion and swinging arms 37 secured to it next to the standards. The forward part of the lower ends of each swinging arm is provided with a V-shaped notch for alining and supporting the fastener tongues. The operating lever 3 of the device has a pin 38, which works in the cam slot 39, and oscillates the cam 36, the spindle 35, and arms 37. Links 40 connect the operating lever 3 to the cross-bar 33, which moves up and down with the lever movement. The operation of this form of my device is as follows; A paper fastener 24 is placed in position under the clips, a paper is placed on the ends of the tongues, and the lever 3 being brought down, causes the paper to be forced onto the ends of the tongues.

45 Continued movement of the lever, causes the cam 36 to operate the spindle 35, and arms 37, so that said arms swing back out of contact with the tongues, and out of the path of the paper. The lever 3 then moves the slotted bar 33 down as far as it will go, and the paper with it, so as to come in contact with the paper filed before it. It is possible to press the papers clear onto the fastener by means of the mechanism of the device, and without hand manipulation at the latter part of the operation, as was the case with the form of the device first described.

I claim:

60 1. In a paper filing device, the combination of paper fastener base holding means which release the fastener on drawing it forward, fastener tongue supporting means having straight line engaging and releasing movements, and means for forcing the pa-

pers onto the fastener tongues to perforate and file them.

2. In a paper filing device, the combination of a base, paper fastener holding means carried thereon which release the fastener on drawing it forward, fastener tongue supporting means having right line engaging and releasing movements, and means for forcing the papers onto the fastener tongues to perforate and file them. 75

3. In a paper filing device, the combination of fastener base holding means which release the fastener on drawing it forward, fastener tongue alining and supporting means having engaging and releasing movements at right angles to the tongues, and means for forcing the papers onto the fastener tongues to perforate and file them. 80

4. In a paper filing device, the combination of fastener base holding means which release the fastener on drawing it forward, means for forcing the papers onto the fastener tongues to perforate and file them, a member having means for alining the fastener tongues and for supporting them in position when alined, and means connected with the perforating and filing means for imparting right line engaging and releasing movements to said alining and supporting member. 90

5. In a paper filing device, the combination of a base, a lever mounted on said base, a bar secured to said lever at right angles to the longitudinal axis thereof and having two paper perforating slots, one on each side of said axis, fastener base holding means which release the fastener on drawing it forward, means for alining and supporting the outer parts of the fastener tongues when perforating papers, and means for positively connecting the alining and supporting means with the lever for imparting engaging and releasing movements thereto. 95

6. In a paper filing device, the combination of a base, a lever fulcrumed on said base, a bar having two perforating slots and carried on said lever, a fastener-tongue-alining device having a pair of V-grooves in line with the slots in the bar, and means for giving to and fro movements to said alining device and the V-grooves therein, so as to bring the fastener tongues in line with the perforating slots. 110

7. In a paper filing device, the combination of a base, a lever fulcrumed on said base, a bar carried on said lever at right angles to the lever axis and having two paper perforating slots, one on each side of said axis, a member having two V-grooves in line with the paper perforating slots and adapted to aline and support the fastener tongues, guides for said V-grooved member, a link connecting said lever to the V-grooved member, and one or more clips for holding paper fasteners in position on said base. 115

8. In a paper filing device, the combination of fastener base holding means embodying one or more spring clips which release the fastener on drawing it forward, means for forcing the papers onto the fastener tongues to perforate and file them, and a member having horizontal engaging and releasing movements and embodying means for alining the ends of the fastener tongues 16 and supporting them when perforating papers.

9. In a paper filing device, the combination of fastener base holding means, means for forcing the papers onto the fastener

tongues to perforate and file them, movable 15 fastener tongue supporting means, and means for connecting the perforating and filing means to the tongue supporting means for imparting engaging and releasing movements thereto.

Signed at New York, in the county of New York, and State of New York, this eighth day of May A. D. 1918.

FRED J. KLEIN.
